Primary Examiner — T. Chase Nelson(74) Attorney, Agent, or Firm — Schwabe, Williamson & Wyatt, P.C.(57) CLAIM

I claim the ornamental design for footwear, as shown and described.

DESCRIPTION

FIG. 1 is a front perspective view of footwear, showing my new design;

FIG. 2 is a rear perspective view thereof; and,

FIG. 3 is a right side view thereof.

The dashed lines are included for illustrating environmental structure and form no part of the claimed design.
